UNITED STATES PATENT OFFICE.

WILLIAM GRIEBE, OF BROOKLYN, NEW YORK.

STARTING DEVICE FOR ELECTRIC MOTORS OR THE LIKE.

1,081,827.

Specification of Letters Patent. Patented Dec. 16, 1913.

Application filed February 12, 1913. Serial No. 747,953.

To all whom it may concern:

Be it known that I, WILLIAM GRIEBE, a citizen of the United States, residing in Brooklyn, in the county of Kings and State 5 of New York, have invented certain new and useful Improvements in Starting Devices for Electric Motors or the like, of which the following is a full and clear specification.

10 This invention relates to devices embodying graded resistances for starting motors or the like, and the primary object of this invention is to overcome certain inherent objections appertaining to the complicated structure of resistance boxes as usually constructed. Such resistance boxes are usually mounted on the walls or posts of the motor room, and according to the usual construction, the graded resistances are suspended 15 within a box and connected up with the contact segments on the outside front cover of said box where they are slidably engaged by a switch, which completes the motor circuit through said resistances, successively. In an arrangement like this, if the connections become impaired or 20 as frequently happens, a portion of the resistances burn out, the box is commonly put out of commission for some time 25 and repairs made at the expense of considerable time and labor. To overcome these difficulties and to provide a resistance box which can be used with motors of any desired power merely by inserting an easily 30 removable portion embodying the proper graded resistances the present invention contemplates the provision of suitable contacts in electrical connection with the motor, and a block or slide which can be instantly 35 released and removed bodily from the starting box and a new block or slide carrying like or different resistance elements immediately installed so that when a mishap occurs, or when it is desired to employ the starting 40 box with a machine of different power, the resistance elements can be instantaneously removed and replaced without any appreciable delay.

Other and further objects will appear in 50 the specification in connection with features pointed out in the appended claims, reference being had to the accompanying drawings, in which,

Figure 1 is a front elevation of one embodiment of my invention with the slide or plunger in raised position; Fig. 2 is a trans-

verse section on the line II—II, Fig. 1, parts being shown in plan; Fig. 3 is a vertical section of the same on the line III—III of Fig. 2, parts being shown in elevation; Fig. 4 is 60 a front plan view of the starting box with the cover removed and the plunger or slide in lowered position, the wiring being shown diagrammatically. Fig. 5 is a fragmentary section on the line V—V Fig. 3, parts being 65 shown in elevation; Fig. 6 is a similar view just before the slide reaches the upper end of its movement; Fig. 7 is a section on the line VII—VII, Fig. 5; Fig. 8 is a fragmentary elevation of the lower ends of the rails. 70

In the embodiment of my invention shown on the drawings, the starting box is adapted in its entirety to be mounted upon a wall, post or other suitable support, by means of base board 1 to which a cover or housing 2, 75 is removably secured by means of the screw bolts 3. When this cover is in place, the several parts of the device are well protected from dust and other foreign bodies which may become lodged therein, but when said cover is removed, all of the several parts are 80 freely accessible. This feature taken in connection with the constructive arrangement of the resistance elements on a bodily removable slide to form a reciprocable plunger for varying the resistance in circuit with the electrical machine, such *e. g.* as the motor shown on the drawings, renders the device far less intricate and more accessible 85 than is generally the case in starting boxes 90 of well known design. Adjacent one corner of the base board 1 are mounted binding posts 4 and 5, which are connected respectively to the positive and negative mains 6 and 7 of an electrical circuit, by means of 95 conductors 8 and 9, respectively.

Leading from the binding post 4, and connected to a supporting bracket 11, is a conductor 10. A short wire 12 connects said bracket 11 with a similar bracket 13 disposed above it, said brackets being adapted to reciprocably mount a pair of rods 14, 15, which are rigidly connected to a contact bar 16 which is slidably mounted on the base board 1. A similar contact bar 17 is also 100 provided with rigidly mounted laterally projecting pins 18 and 19 which project through holes in correspondingly spaced brackets 20 and 21 which are connected by a conductor 22. Brackets 11, 13, 20 and 21 105 are connected to the contact bars 16 and 17 by means of wires 23, 24, 25 and 26. Com-

pression springs 27, 28, 29 and 30 serve to adjust the contacting pressure between the bars 16, 17, and the contacts on the resistance carrying plunger. Extending longitudinally of the base board 1 and preferably between the bars 16 and 17, are a pair of guiding contact rails 31 and 32 which serve to constrain the movement of a slide or plunger to be presently described while certain circuits are made and broken. The lower end of the guide rail 31 is electrically connected to the binding post 4 by the conductor 33. The lower end of the rail 32 is connected by a wire 34 with a binding post 35. Another binding post 36 has the bracket 20 connected thereto by a wire 37. Reciprocably mounted on the rails 31, 32 is a plunger which comprises a channel-shaped slide 38 (see Figs. 2 and 4) carrying a yoke bar 39 which is adapted to bridge the rails 31, 32 except when said plunger is in lowermost position when said yoke bar engages a pair of detached sections 40 and 41 which are insulated from the rails 31 and 32 (see Figs. 4 and 8). Adjacent the upper end of rail 32, is an insulated segment 42 which is connected to the binding post 5 by means of a conductor 43. On the back of slide 38 and spaced from the upper end of the yoke bar 39, are a pair of contacts 44 and 45 which are connected to opposite ends of a magnet coil 46 by means of wires 47 and 48. Adjacent the upper edge of the base board 1, an armature 49 is secured to said base board 35 which serves to hold the plunger in raised position by its reaction on the angularly disposed blades 50 which form continuations of the core of said magnet. The contact segment 45 is of insufficient size to bridge the gap 40 between the rail 32 and segment 42. Along one edge of the slide 38 is secured a contact bar 51 which is electrically connected by a bridge wire 52 to the lowermost of a series of contact segments 53, said segments 53 being respectively connected to successive sections of a resistance coil 54 by means of bridge wires 55.

Referring now to Figs. 1 and 3, a plunger operating lever 56 is pivoted at 57 to the front wall of the cover or housing 2, said lever being swung back and forth by means of handle 58 adjacent its outer end. The lever 56 is provided with a longitudinal slot 57 within which slides a stud 58^a which is threaded at its inner end to the slide 38 and has a knurled head 59 at its outer end. When the stud 58^a is taken out, the slide or plunger can be removed bodily through the lower end of the housing without dismantling said housing which is provided with a vertical slot 60 in the front wall of its cover. Referring now to Fig. 4, the armature 61 of the motor shown in this embodiment, is connected by a wire 62 with the binding post 36 and by another wire 63 with

the negative main 7. The field 64 of said motor, is connected on one side by a wire 65 with the binding post 35 and on the other side is joined to the wire 63 which leads to the negative main 7.

The operation of my improved starting box will now be readily understood and briefly stated is as follows: When it is desired to start the motor 61, the lever 56 is raised gradually. The first result is that the rails 31 and 32 are bridged by the coil of magnet 46 through segments 44, 45 and wires 47 and 48. This imperfectly energizes the field 64, the full strength of field being built up after the yoke bar 39 bridges the rails 31 and 32 and completes the circuit 6, 8, 4, 33, 31, 39, 32, 34, 35, 65, 64, 63, and 7. Almost immediately the contact bar 51 and the uppermost segment 53 respectively engage the contact bars 17 and 16 energizing the armature of motor 61 under full resistance. As the upward movement of the plunger continues, the resistance is gradually thrown out. At the upper end of its stroke, the plunger is held in raised position by the energization of the magnet 46, by means of the following circuit, viz: binding post 6, conductor 8, post 4, conductor 33, rail 31, contact 44, wire 47, coil of magnet 46, wire 48, contact 45, segment 42, wire 43, binding post 5, wire 9 and negative main 7. In this way, should the current be interrupted completely, the magnet 46 loses its magnetism and the plunger drops of its own weight so that when the current again comes on, a sudden load will not be thrown on the armature windings. It will, of course, be understood that various modifications can be incorporated in the embodiment shown on the drawings without departing from the spirit of my invention, as disclosed in the appended claims. The motor armature circuit which is progressively made through the contact segments 53, comprises main 6, 8, 4, 10, 11, 23, 16, 53, 55 or 52, 51, 17, 25, 20, 37, 36, 62, motor 61, 63, and main 7.

What I claim is:

1. In a device of the character described, the combination of two spaced positive and negative contact members of an electric circuit, with a graded resistance movably mounted to bridge the gap between said contact members and adapted to be removed as an entirety from its operative relation to said contact members.

2. In a device of the character described, the combination of two spaced positive and negative contact members, with a resistance member in the form of a sliding plunger provided with graded resistances adapted to bridge the gap between said contact members.

3. A starting device for electric motors comprising spaced positive and negative contacts, a slide slidably mounted with re-

spect to said spaced contacts, graded resistances mounted on said slide, and means for successively bridging the spaced contacts with said resistances comprising a contact 5 on said slide in continuous electrical connection with all of said resistances, adapted to contact with one of said spaced contacts, and a series of contacts on said slide respectively connected to said resistances and 10 adapted to contact with the other spaced contact.

4. The combination with an electric motor, of a starting device therefor comprising spaced contacts electrically connected to said motor, a slide slidably mounted with respect to said spaced contacts, graded resistances mounted on said slide, and means for successively bridging the spaced contacts with said resistances, said 15 means comprising a contact strip extending along one edge of the slide in electrical connection with all of said resistances, and a series of contacts respectively connected to said resistances.

5. The combination with an electric motor, of a starting device therefor comprising spaced contacts electrically connected to said motor, a slide slidably mounted with respect to said spaced contacts, graded 20 resistances mounted on said slide, and means successively bridging the spaced contacts with said resistances, said means comprising a contact strip extending along one edge of the slide in electrical connection 25 with all of said resistances, and a series of contacts respectively connected to said resistances, said spaced contacts being resiliently mounted.

6. A starting device for electric motors 40 comprising a pair of spaced positive and negative contacts adapted to be connected to the opposite terminals of a motor, a slide, resistances mounted on said slide to successively bridge said spaced contacts when 45 movement is imparted to said slide, and means for slidably mounting said slide in operative relation to said contacts.

7. A starting device for motors, comprising a track, contacts adjacent said track, a 50 slide on said track and resistances mounted on said slide, said resistances being thereby adapted to successively bridge said contacts.

8. A starting device for electric motors, comprising a pair of approximately upright 55 spaced parallel contact strips, a resistance slide carrying a plurality of resistance elements and suitably mounted to slide over said spaced contact strips, and means for retaining said resistance slide in operative 60 relation to said contact strips, said resistance elements being adapted to successively bridge the gap between said spaced contact strips and said slide being gravity actuated to move it into inactive position when 65 released.

9. A starting device for electric motors, comprising a pair of practically vertical, spaced, parallel contact strips, a resistance slide carrying a plurality of resistance elements and mounted to move in sliding contact with said spaced contact strips, and electromagnetic means for retaining said resistance slide in its raised position in operative electrical relation to said contact strips, said resistance slide being adapted to move down by gravity into inactive position when released from said electromagnetic means. 70

10. A starting device for motors, comprising oppositely disposed contacts adapted to be connected to a motor, a slide adapted to reciprocate between said contacts, said slide being provided with a conducting strip along one edge adapted to slidably engage one of said oppositely disposed contacts, and a plurality of spaced contacts along its other edge adapted to slidably engage the other of said opposite disposed contacts, and a resistance coil mounted on said slide, said coil being connected at one end to said conducting strip and having successive portions thereof electrically connected respectively to the contacts arranged along the other edge of said slide. 80

11. A starting device for motors, comprising oppositely disposed contacts adapted to be connected to a motor, a slide adapted to reciprocate between said contacts, said slide being provided with a conducting strip along one edge adapted to slidably engage one of said oppositely disposed contacts, and a plurality of spaced contacts along its other edge adapted to slidably engage the other of said oppositely disposed contacts, and a resistance coil mounted on said slide, said coil being connected at one end to said conducting strip and having successive portions thereof electrically connected respectively to the contacts arranged along the other edge of said slide, said oppositely disposed contacts being suitably mounted to give laterally as the slide moves back and forth. 90

12. In a starting device for electric motors, a base member, parallelly arranged metallic strips on said base member, said strips being adapted to be electrically connected to a motor, a slide reciprocably mounted on said base member between said strips, said slide being provided with a metallic strip adapted to slidably engage one of said parallel strips and a series of contact segments adapted to slidably engage the other of said parallel strips, and a resistance coil connected at one end to said strip on the slide and comprising successive portions respectively connected to said contact segments. 115

13. In a starting device for electric motors, a base member, parallelly arranged metallic strips on said base member, said strips 120

125

130

being adapted to be electrically connected to a motor, a slide reciprocably mounted on said base member between said strips, said slide being provided with a metallic strip 5 adapted to slidably engage one of said parallel strips and a series of contact segments adapted to slidably engage the other of said parallel strips, and a resistance coil connected at one end to said strip on the slide and 10 comprising successive portions respectively connected to said contact segments, said base member being vertically arranged and provided adjacent its upper end with electromagnetic means for sustaining the slide in 15 upper position.

14. In a starting device for electric motors, a base member, parallelly arranged metallic strips on said base member, said strips being adapted to be electrically connected to 20 a motor, a slide reciprocably mounted on said base member between said strips, said slide being provided with a metallic strip adapted to slidably engage one of said parallel strips and a series of contact segments adapted to 25 slidably engage the other of said parallel strips, and a resistance coil connected at one end to said strip on the slide and comprising successive portions respectively connected to said contact segments, said base member being vertically arranged and provided 30 adjacent its upper end with electromagnetic means for sustaining the slide in upper position, said electromagnetic device being automatically connected up independently of 35 the motor circuit at the end of the slide's upward movement.

15. A starting device for electric motors, comprising a base member provided with a pair of spaced rails, a slide provided with a 40 bar adapted to bridge said rails, said bar and rails being adapted to reciprocably mount the slide on said base member, spaced contacts arranged along opposite edges of said slide, said contacts being adapted to be electrically connected with a motor, a conducting strip mounted on said slide to engage 45 one of said contacts, a series of contact segments arranged to successively engage the other of said contacts, a plurality of resistances mounted on said slide, said resistances being connected up in series to said conducting strip and respectively connected to said contact segments, means adapted to connect 50 one of said rails with the field of said motor,

and means for connecting the other of said rails with a source of current.

16. A starting device for electric motors, comprising a base member provided with a pair of spaced rails, a slide provided with a bar adapted to bridge said rails, said bar and rails being adapted to reciprocably mount the slide on said base member, spaced contacts arranged along opposite edges of said slide, said contacts being adapted to be electrically connected with a motor, a conducting strip mounted on said slide to engage one of said contacts, a series of contact segments arranged to successively engage the other of said contacts, a plurality of resistances mounted on said slide, said resistances being connected up in series to said conducting strip and respectively connected to said contact segments, means adapted to connect one of said rails with the field of said motor, and means for connecting the other of said rails with a source of current, an electromagnet carried on the upper end of said slide, an armature therefor adjacent the upper ends of said rails, and means for energizing said magnet at the upper end of the slide's movement.

17. A starting device for electric motors, comprising a base member provided with a pair of spaced rails, a slide provided with a bar adapted to bridge said rails, said bar and rails being adapted to reciprocably mount the slide on said base member, spaced contacts arranged along opposite edges of said slide, said contacts being adapted to be electrically connected with a motor, a conducting strip mounted on said slide to engage one of said contacts, a series of contact segments arranged to successively engage the other of said contacts, a plurality of resistances mounted on said slide, said resistances being connected up in series to said conducting strip and respectively connected to said contact segments, means adapted to connect one of said rails with the field of said motor, and means for connecting the other of said rails with a source of current, said slide being removable from the rails on which it reciprocates.
